(57) **CLAIM**

The ornamental design for a utility terrain vehicle, as shown and described.

DESCRIPTION

FIG. 1 is a left perspective view of the utility terrain vehicle showing my new design thereof;

FIG. 2 is a left side view thereof;

FIG. 3 is a right side view thereof;

FIG. 4 is a top view thereof;

FIG. 5 is a front view thereof; and,

FIG. 6 is a rear view thereof.

The broken lines showing of portions of the utility terrain vehicle are included for the purpose of illustrating environmental structure and form no part of the claimed design.
